CONCRETE FINISHING FLOAT

Filed Aug. 13, 1929

UNITED STATES PATENT OFFICE

BYRON R. SMITH, OF HOBART, INDIANA

CONCRETE FINISHING FLOAT

Application filed August 13, 1929. Serial No. 385,637.

This invention relates to floats for finishing the surface of concrete or for use under like circumstances and particularly to a float having a relatively large area and to be used 5 for relatively large work.

The general object of the invention is to provide a float of this character which is light, simple in construction, which is rigid and which provides for an improved manner 10 of attaching a handle to the float.

Other objects will appear in the course of the following description.

My invention is illustrated in the accompanying drawings, wherein:—

15 Figure 1 is a side elevation of a concrete float constructed in accordance with my invention;

Figure 2 is an enlarged cross section thereof.

20 Referring to the drawings, 10 designates a board which constitutes the bottom of the float which may have any desired dimensions. Thus for instance, the board may have a width of approximately six inches 25 or more and a length of ten feet or more. It will be understood, however, that the dimensions of this board may be varied within very wide limits and that the above dimensions are merely given for illustration.

25 Attached to the board is a triangular metal body 1 designated generally 11 preferably formed of a single sheet of metal bent so as to form a body which is triangular in cross section. To this end, one margin of the sheet 35 is formed with the vertical flange 12.

The sheet is then bent downward and outward at 13 and then folded upon itself to form a double ply flange 15, then extended along the face of the board as at 16 and then 40 again folded to form a double ply flange 17 and then extended upward as at 18 and the margin of the metal is bent over the flange 12 as at 19. The two plies of material will be held by a bolt 20. I do not wish to be

45 limited to making this triangular body of one sheet of metal as it may be made of a plurality of sheets of metal engaged with each other by bolting, soldering or riveting. Screws spaced relatively short distances apart 50 and designated 21 are disposed at intervals

through the flanges 15 and 17 and extend into the flat board 10.

Disposed at the middle of the body 11 and projecting laterally therefrom is the triangular portion of sheet metal designated generally 22. This is preferably formed of a sheet of metal bent at its upper edge to provide a portion 23 extending parallel to the edge of the flange 12 and having a flange 24 resting against the folded metal 19 and 55 bolted thereto by the bolt 20. The sides or wings of this member 22 extend downward and outward in divergent relation as shown in Figure 1 and at the lower edge are provided with a flange 25 through which screws 60 21 on that side may pass. Thus the bolt 20 and the screws 21 hold this pyramidal body 22 in place against the triangular body 11 and rigid therewith.

It will be seen that the body 22 is approximately pyramidal in form, though not an equi-lateral pyramid. At the apex of the pyramidal body, there is a projecting socket 26 into which a wooden handle may be inserted. It will be understood that the triangular body 11 is closed at its ends by metallic end pieces 27 which may be riveted to the side walls of the body 11.

In finishing concrete with a wooden float board, the face of the board that is in contact 70 with the wet concrete has a tendency to swell and thus the board turns up at the ends or twists and warps. A float board in this condition is no longer useful, as it must be straight and free from warps in order to prevent irregularities in the surface finished. To this end, I fasten the float board 10 to the metal top at close intervals for practically 75 the entire length of the board.

The metal top is hollow because the float 80 must not be too heavy or it will tend to pull the wet concrete out of position when drawn over the surface finished. It must be light enough for a workman to be able to handle with comparative ease both during the finishing operation and moving it about the work. The triangular cross section is used in the body 11 because this secures rigidity 85 against bending strains in all directions and is particularly rigid against any twisting 90

movements which it must stand in order to prevent the board from warping or twisting.

The flange at the top is made of three plies in order to prevent any dirt or cement from passing through the crack which would be left if it were not made as shown. This extra ply of metal gives it more strength at the top which is very desirable.

10 The plates 27 at the ends of the triangular portion are used to keep out cement and dirt which if allowed to enter would increase the weight. The end plates also add to the rigidity at the end, thereby allowing the tapering of the ends of the metal top. This reduces the weight, eliminates an undesirable sharp corner and increases the efficiency and safety of the float.

20 The hollow pyramidal member 22 is used because it distributes the stresses over a longer portion of the float and holds the handle rigid relative to the float. The pyramidal member may vary considerably in dimensions, but the center line of the handle would be well above the center of gravity of 25 the float body and placed at an angle a little above horizontal as this facilitates the operation of the float.

20 The advantage of this type of float over the ordinary type is that it can be used two or three construction seasons with no care except the changing of float boards when they are worn out, while an ordinary float does well to stay in useful shape a week and more often they have to be trued several 35 times a day unless they are constructed very heavy.

I claim:—

1. A concrete float comprising a float board, a hollow body of sheet metal attached 40 to said board and triangular in cross section, and a pyramidal member of sheet metal attached to the body adjacent its middle and projecting laterally therefrom and having a handle socket at its outer end.

2. A concrete float comprising a float board, an elongated sheet metal body having basal flanges resting against the float board and having a flange extending along the upper corner of the body, attaching devices passing through said basal flanges, a substantially pyramidal sheet metal member having flanges engaging against one of the basal flanges and against the upper flange of the body by said attaching devices, the outer end 55 of the pyramidal portion having a handle socket.

3. A float for concrete comprising a float board, a hollow body of thin sheet metal attached at intervals to the margin of the board 60 around the whole extent of the margin and extending upward from the float board, and a handle socket supported from said body approximately at its middle and extending outward from one side of the body.

35 4. A concrete float comprising a float

board, a hollow body of sheet metal triangular in cross section, the body having the same form in plan as the plan of the board and being attached to the board at short intervals around its entire perimeter, and a handle 70 socket operatively supported upon said body adjacent its middle and extending laterally from said body.

5. A concrete float comprising a float board, a hollow body of sheet metal attached 75 to said board and extending substantially over the entire area of the top face of the float board and attached at short intervals to the float board, and a hollow sheet metal member attached to the body adjacent its 80 middle and projecting laterally therefrom and having a handle socket at its outer end.

In testimony whereof I hereunto affix my signature.
